UNITED STATES PATENT OFFICE.

GUY BENNETT WAITE, OF HOBOKEN, NEW JERSEY.

CENTER FOR FIREPROOF ARCHES.

SPECIFICATION forming part of Letters Patent No. 655,426, dated August 7, 1900.

Application filed January 28, 1899. Serial No. 703,756. (No model.)

To all whom it may concern:

Be it known that I, GUY BENNETT WAITE, a citizen of the United States, residing in Hoboken, county of Hudson, and State of New Jersey, have invented a new and useful Improvement in Centers for Fireproof Arches, of which the following is a specification.

My invention relates to an adjustable centering or temporary support for arches used in the construction of floors for fireproof buildings which can be adapted to the variation in spans and which will be simple and light to handle.

Brick or terra-cotta arches used in floor construction require temporary supports to sustain them in place until the mortar between the joints is thoroughly set and the arch is able to carry itself. Heretofore the centering has been constructed of heavy woodwork hung to the steel beams by hangers which hook over the flanges of the beams and which must be newly constructed for each different arch. All of these centers are cumbersome and heavy to handle, and in the case of the segmental-arch center are expensive to construct, as after being once used they are, as a rule, of no future use.

In my system of construction the centers are adjustable to any span and may be used as often as desired and are light to handle. I attain these objects by the mechanism illustrated in the accompanying drawings, in which—

Figure 1 shows a cross-section of my centers in place ready to receive arches. Fig. 2 is a plan view with the tops of the steel beams removed and with a portion of the centering cut off to show one complete rib. Figs. 3 and 4 are top views of two forms of my centering. Fig. 5 is a plan view showing in a partially-extended position the centering illustrated in Fig. 4. Fig. 6 is a detail of the fastening of the centering shown in Fig. 4. Figs. 7, 8, and 9 are details of construction of the supporting-ribs.

In all views like letters refer to like parts.

My centering consists usually of supporting-ribs *a*, Figs. 1 and 2, which go in between the flanges *f* of the beams I and are hooked thereto by means of hangers *h* and centers *F'*, stretched over said ribs. The supporting-rib *a* is composed of two members *a'* and *a''*, which

slide over each other to accommodate any span and when used for segmental arches being both bent to the same curve maintain the same curve for all spans. To each member *a'* and *a''* is rigidly attached a hanger *h*, which will be described later. To the member *a''* is rigidly attached a simple pendent hook-shaped yoke *s*, (see detail Fig. 7,) bent around so as to support the member *a'*, the latter being free to slide through it. To the member *a'* is likewise attached a portion of the clamp *c*. This clamp *c* performs the same function with respect to the member *a''* that the yoke *s* does with respect to the member *a'*, the member *a''* sliding through the clamp *c*. The clamp *c* is composed of two parts *c'* and *c''*, neither of which projects above the rib *a*. *c'* is fastened to the member *a'* and is notched at *n* to receive the bolt *b*, which bolt may have a nut *m* or be tapped into part *c''*. When the bolt *b* is loose, *a''* can slide freely on *a'*, but when the bolt *b* is tightened the two members *a'* and *a''* are held firmly together by the clamp-jaws *c'* and *c''*. By means of the notch *n* the bolt *b* receives its support from *a'* and in turn supports the end of *a''*.

The hangers *h* are so constructed that they can readily be removed after the arches are in place. To accomplish this the upper portion of the notch in the hanger itself and the top of the hanger are cut on curves with center at a point *p* within the contour of the hanger. Thus when the ribs are to be removed the clamp *c* is loosened and the bolt *b* taken out of the notch *n*, allowing the members *a'* and *a''* to drop. The hanger and its attached member swings about the point *p* until the head of the hanger is removed from the brickwork. The notches, however, when the ribs are in place should bind the lower flange of the beam with sufficient firmness to prevent the arched ribs from canting in use. Although their use is preferable, I do not wish to restrict myself in all cases to the use of the details, as many other constructions which will hold *a'* and *a''* together and allow the movements described will sufficiently answer the purpose. I have, for instance, constructed rib *a* by simply inserting a bolt through a long slot *K*, cut in one member and through a hole of proper size in the other member, thus allowing the two members to slide over each other.

the full length of the slot. This construction is, however, more expensive to manufacture and more difficult to take down after the arch is set. When, as is usually the case, 5 it is not desirable to place the ribs *a* close enough together to lay the arches directly on them, centers *F* or *F'* are stretched over said ribs.

Centers *F* and *F'* are made up of narrow 10 slats *o* and *v* joined together, so that pieces *o* are connected to each other and *v* are also connected to each other, but *o* are free to move on *v*. Straps *d* connect the former and straps *e* connect the latter. Where *o* and *v* 15 overlap each other, straps *d* and *e* are usually fastened on both the top sides and the bottom sides of the slats and form inclosures through which the other set of slats can slide. Thus slats *o* pass through between the straps 20 *e*, fastened on the top side and the bottom side of the ends of slats *v*; also, slats *v* pass through between the straps *d*, fastened on the top side and on the bottom side of the ends of slats *o*. It is thus seen that the center 25 *F*, composed of sets of slats *o* and *v*, can be extended more or less longitudinally, as required, all as indicated in Fig. 2, or it can be entirely closed up, as shown in Fig. 3. These centers are made in convenient sizes and of 30 lengths to be readily handled, and are usually carried to the place where they are to be used, closed together, as shown in Fig. 3, and are when in place pulled out until the entire space which it is desirable to cover is thus 35 completed.

It will seldom be found that the width of the arch will be exactly covered by centers *F*, which centers are usually made of the same width. To complete the unfinished space 40 which has been left after using several widths of centers *F* and also to exactly cover irregular spaces which are wider at one end than at the other or spaces which are not inclosed by straight lines, centers *F'*, Figs. 2, 4, and 45 5, are used. The construction of *F'* allows of expansion or contraction both lengthwise (similar to *F*) and crosswise. The only difference between the construction of *F* and *F'* is in the straps *d* and *e*. In *F* the straps *d* and *e* 50 will usually be made in one continuous piece extending entirely across all slats *o* and *v*, and in *F'* the straps *d* and *e* are made in separate pieces, (see Fig. 6,) each piece extending from one slat only to the next adjacent slat of the 55 same order—thus from *o* to *o* or from *v* to *v*. These short straps are made with a small nail or screw hole near one end and with a long slot extending throughout a considerable distance of the body of the straps. A nail or a 60 screw passing through the small hole in this strap (see Fig. 6) fastens it to the first slat *o*. Now the next slat *o* (when in its normal position) will come under the central part of the slot *t* of strap *d*, Fig. 6. The nail or the 65 screw which passes through the small hole in a second strap *d'* belonging to the next adjacent slat *o* also passes through the slot of

strap *d*. Thus the entire center *F'* is made by each strap lapping over its predecessor, and the nail or the screw which fastens each 70 strap *d* or *d'* to *o* passes through the slot of the strap underneath and into the slat *o*. In this way *F'* can be made to expand sidewise by means of slot *t*, Fig. 6, allowing *o* to move away from or toward the next adjacent slat, 75 the amount of such movement depending on the length of the slot *t*.

I do not restrict myself to the particular detail here shown, Fig. 6, to allow of the expansion crosswise, as many similar devices 80 can be used to answer the same purpose of the slot *t*.

Having substantially described my invention, what I claim as original, and desire to secure by Letters Patent, is—

1. An adjustable centering for arches composed of supporting-ribs and expanding centering resting upon the said ribs, substantially as described.

2. An adjustable centering for arches composed of adjustable ribs, *a*, and expanding centering, *F*, resting upon the said arches, substantially as shown and described.

3. An adjustable centering for arches composed of slats arranged in sets, each set being fastened together by a device which will allow the extension of the centering while preserving its capacity to act as one piece, all substantially as set forth.

4. An adjustable centering for arches consisting of slats each set of said slats being fastened together by straps which allow the extension crosswise of the center while preserving its capacity to act as one piece, substantially as described.

5. An adjustable centering for arches composed of slats *o* and slats *v*, each set of slats being fastened together by straps *d* and *e* having longitudinal slots to allow of the expansion of the centering crosswise, substantially as shown and described.

6. An adjustable centering for arches consisting of ribs *a* each composed of two lapping members *a'* *a''* with means for supporting their outer ends, a yoke *s* on the member *a''* hooked beneath the other, a clamp on the member *a'* having a notch opening longitudinally of the rib, and a pin on the member *a''* removably engaging said notch, substantially as shown and described.

7. An adjustable centering for arches consisting of ribs, each in two lapping members with supporting-hangers at their outer ends, a yoke secured on one member and hooked under but not over the other, and a clamp secured on the last-mentioned member and detachably engaging the first-mentioned, substantially as shown and described.

8. An adjustable centering for arches consisting of ribs, each in two lapping members with supporting-hangers at their outer ends, means for supporting the inner end of one member from the other, and a clamp in two parts one secured to the last-mentioned mem-

ber and notched and the other held to the first-mentioned member by a bolt removably engaging said notch, substantially as shown and described.

5 9. An adjustable centering for arches consisting of supporting-ribs, *a*, hung to the flanges of the beams by means of clips, *h*, having edges curved about the center, *p*,

within the contour of the clip to facilitate the removal of said ribs from the arches, substantially as set forth.
